APPARATUS FOR RAILWAY SIGNAL SYSTEMS

Frederick T. Fereday, Louisville, Ky., assignor to
The Union Switch and Signal Company, Swiss-
vale, Pa., a corporation of Pennsylvania

Application January 6, 1944, Serial No. 517,197

2 Claims. (Cl. 246—38)

1

My invention relates to apparatus for railway signal systems, and more particularly to apparatus for such systems using coded track circuit energy.

Railway signal systems using coded direct current track circuits are not dependent upon a transmission line which is subject to broken line wires caused by weather and other conditions. Heretofore the arrangement for coded direct current track circuits has been to use two sources of current, a relatively large 10 or 12 volt battery for operating the code transmitters and a single cell or low voltage battery for the track circuit. Such two battery arrangement adds to the cost and maintenance. Also there is a certain loss of energy in the current limiting resistor usually interposed in the connection between the track battery and the rails.

Accordingly, a feature of my invention is the provision of railway signal systems incorporating novel and improved track circuit coding apparatus.

Another feature of my invention is the provision of apparatus for track circuits using coded direct current wherewith only a single battery is required.

Again, a feature of my invention is the provision of track circuit apparatus of the type here involved wherewith the code transmitter is connected in series with the track battery taking the place of the usual current limiting resistor and the energy usually consumed in such resistor is utilized for operation of the code transmitter.

Still another feature of my invention is the provision of railway signal apparatus incorporating novel approach control means to cooperate with coding track circuit apparatus to effect an approach control for two sections in advance of a train.

Other features, objects and advantages embodying my invention will appear as the specification progresses.

The features, objects and advantages embodying my invention are accomplished by providing a low voltage code transmitter that is operable from the usual low voltage track battery, and approach control apparatus of the "feed-back" code principle arranged to cooperate with such transmitter. This code transmitter is made to operate on the energy usually consumed in the current limiting resistor interposed between the track battery and the track rails and it is connected in series with the track battery through a contact on a first armature of the transmitter causing such first armature to oscillate. The transmitter

2

is constructed to be mechanically tuned to have a predetermined frequency of oscillation, and thus the track circuit current is periodically interrupted at a rate corresponding to the oscillating frequency predetermined for the code transmitter.

Preferably, the code transmitter is constructed with a second armature which is biased so that this second armature is operated only when the energizing current flowing in the winding

of the transmitter is of a relatively high value. This second armature is adjusted to remain at its biased position with the respective track circuit unoccupied and to be attracted to a picked-up position when a train enters the section to shunt

the rails and the track circuit current is increased. This second armature is used to provide an approach control. As an alternative, the second armature of the transmitter can be replaced by a relay, the winding of which is connected in

series with the code transmitter winding in the track battery connection, and this relay is adjusted to be picked up only when the track circuit current is increased due to a train occupying the section.

The approach control apparatus also includes means governed by the code following track relay to supply feed-back current impulses to the track rails during each off code period of the track circuit current and an approach relay connected to

the rails through a contact carried on the first armature of the code transmitter. This last mentioned contact is closed as the first armature is moved to its attracted position, and the approach relay is connected across the rails each off

code period of the track circuit current to receive the feed-back current impulse supplied to the rails at the relay end of the track circuit. As an alternative, this approach relay may be connected across the rails through a rectifier dis-

posed to pass the feed-back impulses, but block the flow of current from the usual track battery. This approach control relay and the second armature of the code transmitter provide two approach control conditions, one of which becomes

effective when a train enters the section next in the rear of the associated section, and the second of which condition becomes effective when the train enters the associated section.

If more than two different control conditions of the coded track circuit current are required, the traffic controlled circuits are arranged to pole change the connection of the track battery, the code transmitter being operable with equal efficiency by current of either polarity. In this way the track circuit current is coded at a pre-

selected code rate, and is of either positive or negative polarity according to traffic conditions. When the track circuit is polarized, a polarized code following track relay is provided. Again, more than two different control conditions may be provided by using code transmitters of different predetermined operation frequencies and arranging the traffic controlled circuits to selectively connect these transmitters into the track circuit according to different traffic conditions.

I shall describe three forms of apparatus embodying my invention, and shall then point out the novel features thereof in claims.

In the accompanying drawings, Figs. 1 and 2 are diagrammatic views showing a first and a second form of apparatus, respectively, embodying my invention when used with polarized track circuits. Fig. 3 is a diagrammatic view showing a form of apparatus embodying my invention for track circuits using currents of different code rates.

In each of the three views like reference characters are used to designate similar parts.

Referring to Fig. 1, the reference characters 1a and 1b designate the rails of a stretch of railway over which traffic normally moves in the direction indicated by an arrow, and which rails are formed by insulated rail joints with consecutive track sections of a signal system, and of which sections only the one section D—E and the adjoining ends of the two adjacent sections are shown, because these are sufficient to illustrate the principle of my invention.

Each track section is provided with coded track circuit apparatus, control relays, wayside signals and approach control apparatus.

The type of wayside signal to be used is immaterial, and signals SD and SE for section D—E and the section next in advance of section D—E are of the color light type capable of displaying a red lamp R, a yellow lamp Y and a green lamp G, for stop, approach and clear signal indications, respectively.

The track circuit apparatus for each section includes supply means connected across the rails at the exit end of the section and code following relay means connected across the rails at the entrance end of the section. Thus at the junction of adjacent sections, such as location E, for example, there are placed the code following relay means for the track circuit of the section immediately in advance and the supply means for the track circuit of the section immediately in the rear.

The supply means for the track circuit of section D—E includes a track battery BE and a code transmitter CT. The battery BE is preferably of the split battery type having a positive terminal B3, a negative terminal N3 and a mid terminal C. Thus this battery is capable of supplying current of either polarity at the low voltage used for track circuits.

The code transmitter CT may take different forms, and preferably it is of the relay type. Transmitter CT is provided with a first armature or contact member 4 and a second armature or contact member 5. The first armature 4 is biased by weight, or otherwise, to a first position where it engages a contact 6 and is attracted to a second position where it swings out of engagement with contact 6 and into engagement with a contact 7 when a winding 8 of the transmitter is energized. With winding 8 energized through contact 4—6, the armature 4 oscillates between its two positions at a frequency prede-

termined by the weight and construction of the parts. By way of illustration to aid in understanding my invention, I shall assume that transmitter CT is constructed for armature 4 to have an operation frequency of 15 times per minute, it being in engagement with each contact 6 and 7 for substantially one-half of each operation cycle. The second armature 5 is spring or otherwise biased to a released position and is attracted against the force of its bias to a picked-up position when the transmitter is energized at a relatively high preselected energy level. That is, when code transmitter CT is supplied with current of a relatively low value but sufficient for proper operation of the first armature 4, the second armature 5 is retained at its released position by that when current of a relatively high value flows in winding 8, armature 5 is picked up to engage a front contact 9, the armature 4 being operated at its predetermined frequency by such increased current.

Code transmitter CT is energized by track battery BE, winding 8 and contact 4—6 being interposed in series in the connection of track battery BE to the rails of the section D—E. To be explicit, a circuit can be traced from positive terminal B3 of battery BE, either through front contact 10 of a relay ED to be referred to later, or through front contact 11 of a relay EH, also to be referred to later, and back contact 12 of relay ED, wire 13, thence through winding 8 and contact 4—6 of the transmitter, wire 14 to rail 1b, through the track relay of the associated track section, to be described hereinafter, or through a train shunt if a train occupies the section, track rail 1a, and wire 15 to the center terminal C of battery BE. Again, a circuit can be traced from the negative terminal N3 of battery BE through back contacts 16 and 12 of relays EH and ED, respectively, wire 13 and thence as previously traced to the center or mid terminal C of the battery. Thus, when relay ED is picked up to close front contact 10, or relay EH is picked up to close front contact 11, and relay ED is released to close back contact 12, the track battery BE is connected to the rails of the section D—E through the code transmitter and the track circuit is supplied with coded current of what I shall call positive polarity. When both relays EH—and ED are released, the track circuit current is coded and it is of what I shall call negative polarity. If the track section D—E is unoccupied, the value of the track circuit current is of a normal or relatively low value, and the second armature 5 of the code transmitter remains at its released position. If a train occupies the section the track circuit current is increased and the second armature 5 is picked up to close front contact 9.

The code following track relay means for the track circuit of section D—E may be any one of several different arrangements of the polarized type. In Fig. 1, two code following neutral relays DR1 and DR2 are connected in multiple to the rails through rectifiers 17 and 18, respectively, the arrangement being such that relays DR1 and DR2 are operated by current of positive and negative polarity, respectively. The connection of relay DR1 can be traced from rail 1b through wire 19, rectifier 17 in its forward direction, winding of relay DR1, wire 20, back contact 21 of a relay DH to be referred to shortly, and wires 22 and 23 to rail 1a. The connection for relay DR2 extends from rail 1a through wire 23, rectifier 18 in its forward direction, winding of relay DR2,

wire 24, back contact 25 of a relay DD to be referred to shortly, and wires 26 and 19 to rail 1b. It follows that relay DR1 is code operated when coded track circuit current of positive polarity is supplied to the track circuit in the manner explained hereinbefore, and relay DR2 is operated by track circuit current of negative polarity.

It is to be pointed out that code following track relays ER1 and ER2 for the track circuit of the section next in advance of section D—E are connected to the rails in a manner similar to the relays DR1 and DR2 and relays ER1 and ER2 are operated in response to coded track circuit current of positive and negative polarity, respectively, supplied to the track circuit of the section next in advance.

Relays DD and DH at location D are control relays governed by the code following track relays DR1 and DR2, and these control relays govern in turn the signal SD and the track circuit for the section next in the rear of section D—E. Similarly, control relays ED and EH at location E are governed by the track relays ER1 and ER2 and these control relays govern in turn the signal SE and the track circuit for section D—E. Looking at location E, relay EH is governed by relay ER2 through a condenser 27, which functions as a secondary source of energy. When relay ER2 is picked up, the condenser 27 is connected to a charging circuit which includes a battery the terminals of which are designated B10 and N10, and which charging circuit extends from terminal B10 through front contact 28 of relay ER2, condenser 27, wire 29, and to terminal N10 through three alternative paths which include front contacts 30, 31 and 32 of relays AP, FTP and APP, respectively, and which relays are a part of the approach control apparatus to be described hereinafter. Then, when relay ER2 is released to close back contact 33, the condenser 27 is connected across a winding of relay EH and relay EH is energized due to the discharge of the condenser. Consequently, when relay ER2 is operated at a code rate, the control relay EH receives an energizing impulse each code cycle, and it is retained picked up from one code cycle to the next by virtue of a slow release period provided for the relay due to a rectifier 34 connected across its winding. Such energization of relay EH is effected, however, only if one of the approach relays AP, FTP or APP is picked up to close the respective front contact 30, 31 or 32. In a similar manner, the track relay ER1 controls relay ED. Relay ER1 when picked up completes a charging circuit for a condenser 36, such circuit extending from terminal B10 through front contact 35 of relay ER1, condenser 36, wire 29 and to terminal N10 by the three alternative circuit paths explained in connection with the charging circuit of condenser 27. When relay ER1 is released, closing back contact 37, condenser 36 is connected to a winding of relay ED and relay ED is energized by the discharge of the condenser. Relay ED is made slow to release by a rectifier 38 connected across its winding and remains picked up from one code cycle to the next. Control relays ED and EH govern the connection of battery BE to the track circuit for section D—E as explained hereinbefore, and also govern operating circuits for the associated signal SE in a manner to be explained when the operation of the apparatus is described.

Control relays DH and DD at location D are controlled by track relays DR1 and DR2 through condensers 57 and 78 as will be apparent by an

inspection of the drawings taken in connection with the description of the control of relays EH and ED.

The approach control apparatus for section D—E includes means at the entrance end of the section to supply a feed-back current impulse, and an approach relay AR having two associated repeater relays AP and APP and another approach relay FTP at the exit end of the section. 5 The means for supplying a feed-back current impulse includes a condenser 39 and a current source. With either relay DR2 picked up to close front contact 40, or relay DR1 picked up to close front contact 41, condenser 39 is charged by a 10 circuit connected to a battery which may be track battery BD at location D, or a separate battery. This charging circuit extends from terminal B3 of the associated battery through either front contact 40 or 41, condenser 39 and to terminal N3 of the same source of current, through a connection, not shown, but which circuit connection would be similar to the connection of a condenser 42 at location E, and which latter condenser supplies the feed-back current impulse for the track circuit for the section next in advance of section D—E, and which connection for condenser 42 includes back contact 43 of relay AP and either front contact 44 of relay FTP or front contact 45 of relay APP. Condenser 39 is connected across 15 the rails of the section D—E through alternative circuit paths, one of which extends from one terminal of the condenser through back contact 46 of relay DR2, front contact 47 of relay DH and wires 26 and 19 to rail 1b; and from the other terminal of the condenser through front contact 49 of relay DH and wires 22 and 23 to rail 1a. The other circuit path extends from one terminal of condenser 39 through back contact 50 of relay DR1, front contact 51 of relay DD and wires 22 and 23 to rail 1a; and from the other terminal of the condenser through front contact 52 of relay DD and wires 26 and 19 to rail 1b. Consequently, when track relay DR2 is operated 20 at code and the approach control relays for the section next in the rear are conditioned so as to complete the connection of the charging circuit for condenser 39 to the terminal N3 of the associated battery, the condenser 39 is charged each on code period, and is connected across the rails to discharge and provide a feed-back code impulse each off code period. It is to be observed that this feed-back current impulse is of a polarity reverse to that of the track circuit current that operates the track relay DR2. In like 25 manner, code operation of track relay DR1 connects condenser 39 to a charging circuit each on code period and connects the condenser across the rails each off code period to supply a feed-back current impulse due to the discharge of the condenser, the feed-back current impulse being of a polarity reverse to the polarity of the track circuit current that operates track relay DR1. 30

Approach relay AR is connected across the rails through second position contact 7 of armature 4 of the code transmitter CT and thus relay AR is conditioned to receive the feed-back current impulse supplied to the rails through condenser 39 in the manner explained above. Repeater relay AP is energized by an obvious circuit including front contact 53 of relay AR and is retained picked up during code operation of relay AR due to the slow release characteristic of relay AP effected through a condenser connected across its winding. 35

Repeater relay APP is provided with an obvious

pick-up circuit including front contact 54 of relay AP, and with a stick circuit which includes its own front contact 55 and back contact 56 of relay FTP. Relay FTP is energized through an obvious circuit including contact 5-9 of code transmitter CT.

Each of the remaining track sections of the signal system of Fig. 1 is provided with apparatus substantially the same as that described for section D-E.

In describing the operation of the apparatus of Fig. 1, I shall assume that section D-E, as well as the section next in the rear and the section next in advance are unoccupied. Under this traffic condition, code operation of either track relay ER1 or ER2 is ineffective to bring about the energization of the respective control relays ED and EH because the charging circuits for the associated condensers 36 and 27 are held open at front contacts 30, 31 and 32 of the approach control relays AP, APP and FTP of section D-E. With control relays EH and ED deenergized, track battery BE is connected to the rails of section D-E for the track circuit to be supplied with coded current of negative polarity, and which coded current operates the track relay DR2 at location D. Operation of relay DR2 at this time is ineffective to govern the associated control relay DH, because the charging circuit for condenser 57 through which relay DH is controlled is not completed at the associated approach control relays in the same way the charging circuit of condenser 27 at location E is not completed through the contacts of the associated approach control relays of section D-E.

No feed-back current impulse is provided for the section next in advance because the charging circuit for condenser 42 is normally open at front contacts 44 and 45 of the approach control relays FTP and APP, respectively. Likewise, no feed-back current impulse is supplied to section D-E because the charging circuit for condenser 39 is open at the contacts of the approach control relays for the section next in the rear in the same manner that the connection of condenser 42 at location E is normally open at the approach control relays APP and FTP. Consequently, under normal conditions, all control relays and approach control relays are deenergized and all wayside signals are dark.

It is to be observed that in place of each track circuit being normally supplied with coded current of negative polarity, as illustrated in Fig. 1, the polarity of the track circuit current may be reversed for alternate track sections to aid broken down insulated rail joint protection.

I shall next assume that a train enters the section next in the rear of section D-E. The shunting of the rails of the section next in the rear increases the flow of track circuit current for that section, and the second armature of the associated code transmitter is picked up to close its front contact, and which contact corresponds to contact 9 of transmitter CT. This causes the approach relay for the section next in the rear, and which relay corresponds to approach relay FTP, to be picked up through the second armature contact of the associated code transmitter, and that relay on picking up closes contacts that correspond to contacts 31, 44 and 58 of relay FTP. The closing of the front contact that corresponds to front contact 44 of relay FTP completes a connection by which the condenser 39 is charged each on code period, so that condenser 39 now supplies a feed-back current impulse each

5 off code period which causes in turn approach relay AR at location E to be operated and the associated repeater relays AP and APP to be energized.

6 The closing of front contact 30 of relay AP completes the circuit by which condenser 27 is charged, and consequently the control relay EH is energized in response to code operation of track relay ER2. Relay EH on picking up to close front contact 11 switches the connection of track battery BE and the track circuit of section D-E is supplied with coded current of positive polarity causing track relay DR1 to be operated in place of track relay DR2. With relay DR1 operated, the associated control relay DD is energized because condenser 18 is now charged each on code period due to the contact corresponding to contact 31 of relay FTP being closed at the corresponding relay for the section next in the rear. Relay DD on picking up to close front contacts 51 and 52 completes the connection for the feed-back impulse for section D-E. Also, the picking up of relay DD to close front contact 60 completes a circuit by which green lamp G of signal SD is illuminated, this circuit being completed through contacts of the approach control relays for the section next in the rear in a manner similar to the control circuit for lamp G of signal SE at location E and which latter circuit is completed at front contact 58 of relay FTP and back contact 61 of relay AP when a train has entered section D-E. Consequently signal SD is approach lighted to display a clear signal, and feed-back impulses are supplied to section D-E.

40 It is to be noted that signal SE remains dark while the train occupies the section next in the rear of section D-E because the control circuits of signal SE are held open at front contact 58 of relay FTP and at back contact 61 of relay AP.

45 It is to be observed that if another train occupies the section next in advance of the section D-E at the time the first assumed train is traversing the section next in the rear of section D-E, the train in the section next in advance shunts relays ER1 and ER2 and both control relays EH and ED are deenergized causing the track circuit current for section D-E to be of negative polarity so that track relay DR2 at location D is operated and control relay DH is energized in response to the charging and discharging of condenser 57. With control relay DH picked up the feed-back impulses are supplied as before, and with front contact 63 closed and relay DD released to close back contact 62, the yellow lamp Y of signal SD is illuminated for the signal to display an approach indication.

50 I shall next assume that the first mentioned train advances and enters section D-E, the section next in advance being considered as unoccupied. The shunting of the rails of section D-E shunts the track circuit current from the relays DR1 and DR2 and also the feed-back current impulse from relay AR. The shunting of both track relays DR1 and DR2 causes both control relays DD and DH to be deenergized with the result the R lamp of signal SD is illuminated through a circuit including back contacts 62 and 106 of relays DD and DH. The shunting of approach relay AR causes this relay to be released and the repeater relay AP is deenergized and released at the end of its slow release period. The shunting of the rails of section D-E causes an increase in the track circuit current so that armature 5 of the code transmitter CT is picked

up to bring about the energizing of approach relay FTP. The picking up of relay FTP opens back contact 56 in the stick circuit for relay APP and that relay is deenergized subsequent to the release of relay AP. With relay AP released to close back contact 43 and relay FTP picked up to close front contact 44, the charging circuit for condenser 42 is completed and feed-back current impulses are now supplied to the rails for the section next in advance to govern the approach relay at the exit end of the section, and which approach relay corresponds to relay AR. Release of relay AP to close back contact 61, and the picking up of relay FTP to close front contact 58 completes the operating circuit to illuminate either the green lamp G or the yellow lamp Y of signal SE according to which control relay ED or EH is picked up in response to traffic conditions in advance of section D—E. If a second train occupies the section in advance to bring about the release of both control relays EH and ED, closing back contacts 64 and 65, the red lamp R of signal SE is illuminated as a stop signal indication.

In the case the increase of track circuit current when the train first enters section D—E is not sufficient to pick up the second armature 5 of code transmitter CT and the current does not reach the value at which the second armature is picked up until the train has advanced some distance into section D—E, the relay APP is retained picked up by its stick circuit and the operating circuit for signal SE is completed at front contact 66 of relay APP. Also the charging circuits for condensers 27 and 36 are completed at front contact 32 of relay APP, and the charging circuit for the condenser 42 is completed at front contact 45 of relay APP until such time as the armature 5 of the code transmitter is operated to bring about the energization of relay FTP.

When this train vacates section D—E shunting relays ER1 and ER2, both control relays ED and EH are released so that the track circuit for section D—E is again supplied with current of negative polarity and the apparatus is restored to its normal condition.

In Fig. 2, the apparatus is the same as that in Fig. 1, except for the means for supplying the feed-back current impulse, and the apparatus at location E only is shown because this is sufficient to fully illustrate this form of apparatus embodying my invention. In Fig. 2 the feed-back current impulse is obtained from the track battery or preferably a separate battery of equivalent voltage, and a relay. Looking at location E of Fig. 2, and assuming that track relay ER2 is being operated in response to coded track circuit current for the section next in advance of section D—E, a circuit for energizing a relay EF is formed each off code period, such circuit being traced from terminal B3 of the respective source of current, through back contacts 68 and 67 of relays ER1 and ER2, winding of relay EF, a rectifier 69, wire 70, back contact 43 of relay AP and either front contact 44 of relay FTP or front contact 45 of relay APP to terminal N3 of the same source of current. Relay EF is provided with a slow pick-up period which is something less than the on code period of the track circuit current. During this slow pick-up period of relay EF, current flows from terminal B3 through back contacts 68 and 67, back contact 71 of relay EF, resistor 72, front contact 73 of relay EH which is picked up due to code operation of relay ER2, wire 74 to rail 1b, through the winding of the approach

relay for the section next in advance and which approach relay corresponds to relay AR for section D—E, track rail 1a, wire 75, front contact 76 of relay EH, wires 77 and 70, back contact 43 of relay AP and either front contact 44 of relay FTP or front contact 45 of relay APP to terminal N3. This feed-back current impulse thus supplied to the rails of the section next in advance will operate the approach relay that corresponds to relay AR and effect the approach control apparatus for that section. If relay ER1 is code operated the circuit for the feed-back impulse is completed at front contacts 104 and 105 of relay ED. It is apparent that the apparatus of Fig. 2 will operate in a manner similar to the apparatus of Fig. 1 under the different traffic conditions and a description of the operation of the apparatus of Fig. 2 need not be further described.

In Fig. 3, in which a form of apparatus embodying my invention using different code rates is disclosed, the stretch of railway is arranged with track sections and wayside signals the same as in Fig. 1, and each section is provided with track circuit apparatus, signal control relays and approach control relays, the same as in Fig. 1.

The supply means for the track circuit of section D—E of Fig. 3 comprises a battery BE1 and two code transmitters CT75 and CT180. The code transmitters CT75 and CT180 are similar in construction to code transmitter CT of Fig. 1, transmitter CT75 being constructed to have an operation frequency of 75 times per minute, and transmitter CT180 an operation frequency of 180 times per minute. It will be understood, of course, that other operation frequencies may be selected for these code transmitters. These two transmitters are also adjusted for their respective second armatures 79 and 80 to be picked up at the same preselected relatively high value of current that was provided for transmitter CT. Battery BE1 is connected to the rails of the associated section through one or the other of the transmitters, a first connection including front contact 81 of control relay EH, winding and contact 82 of transmitter CT180, track rail 1b, track relay or train shunt and track rail 1a and wire 83 to the other terminal of battery BE1. A second connection includes back contact 84 of control relay EH, winding and contact 85 of transmitter CT75 and thence as previously traced for the first circuit connection. Thus when control relay EH is energized, the track circuit for track section D—E is supplied with coded current of the 180 code rate, and when relay EH is released the track circuit current is of the 75 code rate, the polarity of the current being the same for both conditions.

Track relay DR3 for the section D—E is a direct current code following relay connected across the rails through a rectifier 86 which is poled to pass current of the polarity supplied by battery BE1, and to block the feed-back current impulse used for control of the approach control apparatus to be described shortly. At location E, track relay ER3 associated with the track section next in advance is connected to the rails in a manner similar to that of track relay DR3. Track relay DR3 governs control relays DH and DD through a repeater relay TPD and a decoding unit 180DU. Similarly, track relay ER3 governs associated control relays EH and ED through a repeater relay TPE and a decoding unit 180DU. Looking at location E, track relay ER3 when picked up to close front contact 88

11

completes an obvious circuit for energizing repeater relay TPE, and which circuit is completed through front contact 30, 31 or 32 of the relays AP, FTP or APP in the manner explained in connection with Fig. 1. It follows that when relay ER3 is operated at code, the repeater relay TPE is operated at a corresponding code providing the approach control relays are properly conditioned. With relay TPE picked up to close front contact 89, condenser 87 is charged through a circuit completed at front contact 30, 31 or 32, and condenser 87 is discharged through the winding of control relay EH when repeater relay TPE is released to close its back contact 90, during each off code period. With relay EH thus picked up in response to code operation of track relay ER3, the closing of front contact 91 of relay EH completes a circuit for supplying current impulses to the input side of the decoding unit 180DU through front and back contacts 92 and 93 of repeater relay TPE. Decoding unit 180DU may be of any one of the several well-known arrangements, and is shown conventionally for the sake of simplicity. It is sufficient to point out that when current impulses supplied to the input side of the unit are of the 180 code rate the control relay ED connected to the output side of the unit is energized and picked up, but that when the code impulses are of the 75 code rate, the control relay ED is deenergized and released. Control relays EH and ED, together with the approach control relays for section D—E govern the operating circuits for signal SE the same as in Fig. 1. Control relays DH and DD at location D are controlled by repeater relay TPD in a manner similar to that by which relays EH and ED are controlled by relay TPE.

The approach control apparatus of Fig. 3 is similar to that described for Fig. 1, and it is believed that this approach control apparatus of Fig. 3 can best be understood from a description of the operation of the apparatus. It is to be understood, of course, that location D of Fig. 3, and each similar location are provided with apparatus similar to that for location E of Fig. 3.

Normally, that is, when section D—E and the adjacent sections of Fig. 3 are unoccupied, track relay ER3 is code operated, but control relay EH and in turn control relay ED remain deenergized because the circuits for the repeater relay TPE and condenser 87 are not completed at contacts 30, 31 or 32 of the associated approach control relays. With relay EH released, closing back contact 84, the track circuit for section D—E is of the 75 code rate, and track relay DR3 is operated at a corresponding code rate. Thus, in Fig. 3, all control relays and approach control relays are normally deenergized and the signals are dark.

I shall next assume that a train enters the section next in the rear of section D—E. This causes the track circuit current for the section next in the rear to be increased, and the respective second armature of the code transmitter is picked up so that the relay corresponding to relay FTP of section D—E is energized. This closes a front contact corresponding to front contact 31 of relay FTP with the result the repeater relay TPD is operated to bring about the control of relay DH, condenser 94 acting as a secondary source of energy in the control of relay DH. Approach relay ARD and its repeater relay APD at location D will be deenergized due to the shunting of the feed-back impulses by this train entering the section next in the rear, and with

12

relay APD released to close back contact 97 a charging circuit is completed for a condenser 95 through which feed-back current impulses are supplied to the rails of section D—E. This charging circuit for condenser 95 extends from terminal B3 through front contact 96 of track relay DR3, condenser 95, back contact 97 of relay APD and front contact 98 of control relay DH to terminal N3. Condenser 95 is connected across the rails through back contact 99 of relay DR3 and is discharged to supply a feed-back current impulse. This feed-back current impulse is of a polarity to energize approach relay AR at location E which relay in Fig. 3 is connected across the rails through a rectifier 100 poled to block the current supplied by track battery BE1. Relay DR3 will not be energized by this feed-back current impulse due to rectifier 86. With approach relay AR operated by the feed-back current impulses, its associated repeater relays AP and APP are energized. With relay AP picked up to close front contact 30, the energizing circuit of repeater relay TPE and the charging circuit of condenser 87 are completed and control relay EH is energized in response to code operation of the track relay ER3. Control relay EH on picking up to close front contact 81 connects battery BE1 to the rails through code transmitter CT180, so that the track circuit for section D—E is now supplied with current of the 180 code rate, with the result that control relay DD is energized and signal SD is controlled as required to display a clear signal indication.

In the event a second train occupies the section next in advance of section D—E, the shunting of track relay ER3 causes control relay EH to be released so that the track circuit current for section D—E is of the 75 code rate, with the result control relay DH is picked up but control relay DD is released and signal SD is controlled as required to display an approach signal indication.

When the train advances and enters section D—E, the shunting of the rails causes an increase in the track circuit current and the second armature of either code transmitter CT75 or CT180 is picked up with the result the approach relay FTP is energized to close front contact 31. The feed-back current impulses for the section D—E are now shunted so that approach relay AR and its repeater relay AP are deenergized. Control relay EH remains energized because the connection for repeater relay TPE and condenser 87 is now closed at front contact 31 of relay FTP. With relay AP released and relay EH picked up, a charging circuit for a condenser 103 is formed from terminal B3, front contact 108 of relay ER3, condenser 103, back contact 101 of relay AP and front contact 102 of relay EH to terminal N3. Condenser 103 is then discharged through back contact 107 of track relay ER3 for supplying a feed-back current impulse to the rails of the section next in advance. With back contact 61 of relay AP and front contact 58 of relay FTP closed, the operating circuits for signal SE are completed and the clear or approach lamp of the signal is illuminated according to the condition of control relays EH and ED.

The apparatus here disclosed has the advantage that a single battery only is required for each track circuit supplied with coded direct current, different traffic conditions being reflected by the polarity and code rate of the current. Also approach control apparatus cooperating with

13

such track circuit is effective to provide approach control for two sections in advance of a train.

Although I have herein shown and described only three forms of apparatus for railway signal systems embodying my invention, it is understood that various changes and modifications may be made therein within the scope of the appended claims without departing from the spirit and scope of my invention.

Having thus described my invention, what I claims is:

1. In combination with a railway track circuit including the rails of a section and a track relay connected across the rails at one end of said section, a source of direct current, a code transmitter having a first contact member biased to a first position where it engages a fixed contact and operable to a second position where it is out of engagement with said fixed contact when a winding of the transmitter is energized, circuit means including said fixed contact and said contact member to connect said current source across the rails at the end of said section opposite said one end through said winding to code the current supplied to said track circuit for operating said track relay at said code when the section is unoccupied, a second contact member operable by said transmitter to engage a fixed contact only when said transmitter winding is energized at a relatively high value of current to close the last mentioned contact only when a train occupies the section to shunt the rails, and

a first and a second signaling means controlled by said track relay and said second transmitter contact member respectively.

2. In combination with a railway track circuit including the rails of a track section and a track relay connected across the rails at one end of the section and a track battery connected across the rails at the other end of the section, a code transmitter having a first contact member biased to a first position and operable to a second position when its winding is energized, said contact member at its first position and said winding in series interposed in the connection of said track battery to code the track circuit current for code operating said track relay when the section is unoccupied, a second contact member for said code transmitter and which second contact member is biased to a first position and is operated to a second position only when the transmitter is energized at a relatively high value of current to close a front contact when a train occupies said section to shunt the rails, supply means controlled by said track relay when code operated to supply to the rails an impulse of current each code period the track relay is de-energized, a first signaling means including said first contact member at its second position energized by said current impulses when the section is unoccupied, and a second signaling means including said front contact and a current source energized when a train occupies the section.

FREDERICK T. FEREDAY.
